No. 836,584.

PATENTED NOV. 20, 1906.

L. H. KENNEDY.
WATER ELEVATOR.
APPLICATION FILED NOV. 14, 1905.

UNITED STATES PATENT OFFICE.

LOUIS HENRY KENNEDY, OF UNION, SOUTH CAROLINA, ASSIGNOR OF
ONE-HALF TO EDWARD HELTON, OF UNION, SOUTH CAROLINA.

WATER-ELEVATOR.

No. 836,584.

Specification of Letters Patent.

Patented Nov. 20, 1906.

Application filed November 14, 1905. Serial No. 287,300.

To all whom it may concern:

Be it known that I, LOUIS HENRY KENNEDY, a citizen of the United States, residing at Union, in the county of Union and State 5 of South Carolina, have invented certain new and useful Improvements in Water-Elevators; and I do hereby declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to new and useful improvements in water-elevators; and the object of the invention is to produce a simple and efficient means whereby water may be put under pressure within a cylinder in a 20 well and caused to distribute water at different elevations without the use of pumping apparatus.

25 My invention comprises various details of construction and combinations of parts, which will be hereinafter fully described and then specifically defined in the appended claim.

30 I illustrate my invention in the accompanying drawings, in which—

35 Figure 1 is a sectional view through a well, showing the application of my water-elevating device, parts of the invention being shown in elevation. Fig. 2 is an enlarged sectional view through the weighted member which is positioned within the tank, and Fig. 3 is a sectional view on line 3 3 of Fig. 1.

40 Reference now being had to the details of the drawings by letter, A designates a tank, which may be of any size or shape and is provided with a strainer A' at its lower end and an inlet-opening B, which is regulated by a ball-valve B', which latter is held in place by means of a casing B''. Said tank is provided with a reciprocating plunger C, which fits 45 tightly against the inner surface of said tank in which said plunger has a reciprocating movement, and said plunger has flanges C' extending about its lower face, and intermediate said flanges is a disk D.

50 E designates a shell adapted to form a weighted member, and in the lower end of said shell is a block E', resting upon a disk F, and said block E' and the disks D and F and

also the plunger C are held together by means of the bolts G, passed through registering apertures in said parts, and said bolts being held in place by nuts G'. The upper end of said shell E has a block K fitted therein, being held in place by means of the bolts K', which are similar to the bolts G, which hold the block E' in place. Passing through a central aperture in the block K is a rod N, held to said block by means of the nuts N', and the shank portion of said rod is threaded, as at N². 55

O designates rods, the lower ends of which are fastened to the wall of the tank A and their upper ends fastened at O' to a platform or other object about a well or cistern in which the apparatus is positioned. 60

Q designates a plate having a groove upon its upper surface and is fastened to the platform P over the well and is provided with a central aperture, through which the shaft N has a play. 70

75 S designates a wheel having handles S' about its circumference and is provided with a central hub portion T, which has a threaded aperture therein designed to fit the threads N² upon the rod N, and the lower edge of said hub is grooved to receive ball-bearings S², which rest in the groove in the plate Q.

80 Leading from the lower portion of the tank is a pipe J, the upper end of which is provided with a faucet J', and, if desired, branching pipes may be connected therewith, whereby the water may be conveyed to any desired location. 85

85 The operation of my apparatus is as follows: The tank being positioned at the desired depth in a well, it is held therein by means of the rods O, the tank being filled by water coming through the valve-regulated opening in the bottom thereof. When it is 90 desired to apply pressure to the surface of the water in said tank, the weighted member having the plunger secured at the lower end thereof is forced down by turning the wheel S, thus applying the desired pressure to the 95 water within the tank, and when it is desired to draw water the operator by simply turning the faucet will receive a supply coming from the tank, which holds the water underneath the weight at any suitable pressure. 100 By turning the wheel S in a reverse direction 105

the weight may be raised to a location near the upper end of the tank and the supply replenished.

From the foregoing it will be noted that by 5 the provision of the apparatus shown and described a simple and efficient means is afforded whereby water may be conveyed under pressure to various elevations without the intervention of a pumping apparatus.

Having thus fully described my invention, what I claim as new, and desire to secure by 10 Letters Patent, is—

An apparatus for elevating water comprising 15 a tank with a valve-regulated opening in the bottom thereof, an exit-pipe leading from said tank, a plunger with a flange on the under face thereof, the circumference of which fits against the inner surface of said

tank, disks mounted one on each side of said plunger, a weighted shell, a block mounted in the lower end of said shell, bolts fastened to said block, whereby the same is held to 20 said plunger, a block fastened in the upper end of said shell, a threaded rod fastened to said block in the upper end of said shell, a bearing-plate, a wheel having a hub portion 25 with a threaded aperture adapted to receive the threaded portion of said rod, said hub portion designed to contact with said bearing-plate, as set forth.

In testimony whereof I hereunto affix my 30 signature in the presence of two witnesses.

LOUIS HENRY KENNEDY.
